MULTIPLE-BARREL FIREARM

Louis Stiennon, deceased, late of New Haven, Conn., by Roy L. Parsell, administrator, Pine Orchard, Conn., assignor to Winchester Repeating Arms Company, New Haven, Conn., a corporation of Maryland

Application June 20, 1935, Serial No. 27,518

6 Claims. (Cl. 42—40)

This invention relates to an improvement in multiple-barrel firearms, and particularly to that class of multiple-barrel firearms commonly referred to as "over-and-under" firearms, in which the barrels are arranged one over another in a vertical plane.

One object of the present invention is to provide a superior over-and-under multiple-barrel firearm in which the firing mechanism is of simple and reliable nature.

A further object is to provide a superior firearm of the class described, in which hammer blows of substantially-equal force may be exerted upon a plurality of firing-pins or equivalent members.

Another object is to provide a superior over-and-under firearm construction in which the firing of an upper barrel and the firing of a lower barrel may be effected by hammers which are of substantially-corresponding character.

A still further object is to provide a superior firing-plunger arrangement for firearms of the type referred to.

Still another object is to provide a superior over-and-under multiple-barrel firearm in which two coaxial hammers of substantially equal length may reliably effect the firing of two barrels arranged one over the other.

With the above and other objects in view, as will appear to those skilled in the art from the following, considered in conjunction with the accompanying drawings and appended claims, the present invention includes all features disclosed therein which are novel over the prior art.

35 In the accompanying drawings:

Fig. 1 is a view partly in side elevation and partly in vertical section of a so-called "over-and-under" double-barreled shotgun embodying the present invention;

40 Fig. 2 is a longitudinal sectional view taken on the line 2—2 of Fig. 1;

Fig. 3 is a transverse sectional view taken on the line 3—3 of Fig. 1;

Fig. 4 is a similar view taken on the line 4—4 of Fig. 1;

Fig. 5 is a corresponding view taken on the line 5—5 of Fig. 1;

Fig. 6 is a schematic perspective view of the hammers, firing-plungers and associated parts of the gun-structure shown in relative operating positions;

Fig. 7 is a perspective view of the pair of corresponding firing-plungers shown as vertically separated for clarity of illustration;

Fig. 8 is a perspective view of the frame-bridge; and

Fig. 9 is a similar view of one of the complementary hammers.

The particular firearm herein chosen for the 5 illustration of the present invention is of the so-called "breakdown" type and includes a butt-unit and a barrel-unit pivoted together, as is usual in this type of firearm.

The butt-unit comprises in the main a frame 10 generally designated by the numeral 20 and a buttstock 21 rigidly secured to the rear end of the said frame. The barrel-unit comprises in the main an upper barrel 22, a lower barrel 23 and a forestock 24, which latter is provided with a forestock-shoe 25 bearing against the cylindrically-contoured forward end 26 of the frame 20 in the usual manner of breakdown firearms.

The frame 20 has rearwardly projecting from its respective upper and lower walls a pair of 20 substantially-parallel spaced-apart tangs 27 and 28, which are connected together at their rear ends by a substantially-vertical tie-bar 29, into which is threaded a buttstock-bolt 30 serving to rigidly unite the buttstock 21 with the frame 20. 25

Directly below its forwardly-facing standing-breech 31, the frame 20 is provided with a bottom-passage 32 closed by a removable cover-plate or closure 33 and through which various machining operations may be carried on within the interior of the frame prior to the installation of the said cover-plate 33 and through which various features of the mechanism may be introduced, removed and adjusted.

Axially in line with the respective cartridge-chambers 34 of each of the barrels 22 and 23, the standing-breech 31 of the frame 20 is formed with a passage 35 through which the firing-point 36 of one of two corresponding firing-pins or firing-plungers 37—37 is adapted to be forwardly 40 projected and by which it is guided.

The firing-plungers 37—37 respectively serving the upper and lower barrels 22 and 23 are duplicates of each other, as above noted, though reversed in position. The upper firing-pin slopes 45 rearwardly and downwardly, and the lower firing-pin slopes rearwardly and upwardly, and each thereof is formed at its rear end with a head 38 of substantially L-shaped form in cross-section, as particularly well shown in Fig. 7. 50

The respective upper and lower firing-pins 37—37 are so constructed and arranged that their respective L-shaped heads 38—38 "nest together", so to speak, and form a substantially-rectangular cross-sectional figure, each L-shaped portion of 55

which may reciprocate independently of the other in a rectangular bearing-passage 39 formed in a bridge-piece 40 which extends substantially-vertically between the upper and lower tangs 27 and 28 of the frame 20 a relatively-short distance to the rear of the standing-breech 31 of the latter.

Adjacent its bearing-passage 39, the forward face of the bridge-piece 40 is recessed as at 41 to provide clearance for the sloping portions of the respective firing-pins 37. The lower end of the said bridge-piece is provided on its respective opposite sides with depending perforated coupling-ears 42-42 fitting into a recess 43 in the lower tang 28 and secured to the latter by means of a pin 44 extending transversely therethrough and through the respective coupling-ears 42-42 before referred to. Upstanding from the bridge-piece 40 is a pair of complementary cylindrical anchoring-projections 44-44 entering a pair of vertically-extending complementary sockets or passages 45-45 formed in the upper tang 27 of the frame 20, as particularly well shown in Fig. 4.

The firing-pins 37-37 are formed respectively with forwardly-facing thrust-shoulders 46-46 which complement each other when the firing-pins are in place, and are engaged by the respective opposite sides of a washer-like thrust-collar 47 mounted with freedom for reciprocation and tilting upon a guide-plunger 48. The guide-plunger 48 just referred to is provided at its forward end with a conical head 49 seating into a similarly-shaped socket 50 in the rear face of the standing-breech 31. The rear end of the guide-plunger 48 rests in a passage provided by forming each of the heads 38-38 of the respective firing-pins 37-37 with a longitudinal groove 51 of semicircular form in cross-section.

Mounted upon the forward portion of the guide-plunger 48 is a retracting-spring 52 bearing at its forward end against the rear face of the head 49 and at its rear end against the thrust-collar 47 to thereby urge the latter rearwardly and hence urge the respective firing-pins 37-37 in the same direction to rearwardly-extend the respective rearwardly-projecting impact-noses 53-53 thereof beyond the rear surface of the bridge-piece 40. For the purpose of limiting the rearward movement of the firing-pins 37-37 under the urge of the retracting-spring 52, each firing-plunger is formed with a stop-shoulder 37a which is engageable, for the purpose referred to, with the rear wall of the recess 41 in the bridge-piece 40.

When the two corresponding firing-pins 37-37 are in assembled relationship, the respective impact-noses thereof are located in laterally-spaced planes but in substantially the same horizontal plane, while the respective firing-points 36-36 of the said firing-pins are located in different horizontal planes but in substantially the same vertical plane.

The impact-nose 53 of the upper firing-pin 37 is located to the left of the vertical center of the firearm-structure in position to be struck by the impact-face 54 of a left-hand hammer 55, while the impact-nose 53 of the lower firing-pin 37 is located to the right of the vertical center of the firearm-structure in position to be struck by the impact-face 56 of a right-hand hammer 57. Each of the hammers 55 and 57 just referred to are of corresponding outline and are mounted side by side for swinging movement in a vertical plane upon a pin 58 which extends transversely across the lower tang 28 of the frame 20 and

through the respective lower ends of the said hammers.

Each of the hammers 55 and 57 is formed in its inner forward corner with a semicircular notch 59 into which extends the rear end of a cocking-slide 60 mounted in the lower portion of the frame and serving, when the firearm is "broken down", so to speak, to effect the cocking of the said hammers in a manner corresponding in substance to breakdown firearms in general.

Each of the hammers 55 and 57 is formed in its rear face, about midway of its height, with a socket 61 receiving the rounded forward end of a head 62 of a hammer-actuating plunger 63. Each hammer-actuating plunger is encircled by a helical hammer-spring 64 which bears at its forward end against the rear face of the head 62 of its complementary actuating-plunger 63 and at its rear end extends into a bore 65 in the tie-bar 29 and seats against a pin 66 extending transversely thereacross. Thus, each hammer is movable independently of the other and is provided with spring-means exerting a constant effort to swing its upper end forwardly for engagement with the impact-nose 53 of its complementary firing-pin 37.

In its lower rear portion, each of the hammers 55 and 57 is formed with a cocking-notch 67 adapted to be engaged by the cocking-nose 68 of a sear 69, one of which latter is provided for each of the said hammers. The sears 69 of the respective hammers are mounted for pivotal movement about a common horizontal center by means of a fulcrum-pin 70 extending transversely across the lower tang 28 and through each of the said sears.

The mode of actuating the sears 69 may vary widely and such means per se forms no essential feature of the present invention. In the particular firearm shown, a pivotal trigger 71 carries a transversely-movable selector-slide 72 which is shiftable with respect to the said trigger to place it in position for lifting the rear end of either one or the other of the sears 69 to thus operate the same and effect the release of the particular hammer 55 or 57 controlled by the sear in question.

In Fig. 1 of the accompanying drawings, the left-hand hammer 55 is shown in the position which it assumes after having been released to effect the firing of the upper barrel, while the right-hand hammer 57 is shown in its cocked position. When either hammer is released for striking the impact-nose 53 of its complementary firing-pin, the rear face of the bridge-piece 40 serves to limit the forward spring thereof.

By the construction and arrangement shown, the firing of the cartridges in a pair of barrels arranged one above the other may be effected in a simple and reliable manner by means of hammers of substantially the same length, and therefore, having substantially the same impact force under the urge of corresponding hammer-springs, such, for instance, as 64-64.

By means of the present invention, therefore, it is not necessary to employ hammers having their impact-faces located at different distances from their fulcrums, with attendant difficulties to secure appropriate spring strength for each, nor is it necessary to mount the hammer of each firing-pin for pivotal movement about fulcrums displaced vertically with respect to each other.

Furthermore, by the construction above described, the firing-points of each of the firing-pins is assured of a movement parallel with the

axis of the cartridge-chambers of the respective barrels, thus insuring the proper indenting of cartridge-primers despite variations in their distance from the standing-breech, due to factors 5 such, for instance, as variations in the depths of seating of primers in the cartridges, or in variations in the seating of the cartridges themselves in the cartridge-chambers of the barrels.

The substantial parallelism referred to in the 10 appended claims is intended to indicate such a close approximation of true parallelism as will achieve the surety of firing before referred to, and in all instances the degree of parallelism must be such that the axis of movement of one 15 of the firing-points will not intersect the axis of movement of the other firing-point within a distance as far back as the rear end of the butt-stock.

The invention may be carried out in other 20 specific ways than those herein set forth without departing from the spirit and essential characteristics of the invention, and the present embodiments are, therefore, to be considered in all respects as illustrative and not restrictive, 25 and all changes coming within the meaning and equivalency range of the appended claims are intended to be embraced therein.

What is claimed is:

1. In a multiple-barrel firearm, the combination 30 with two barrels arranged one over the other; a pair of independently-operable impact-members; a firing-plunger having an integral angularly-projecting firing-point and an impact-surface engageable by one of the said impact-members and extending forwardly and upwardly at an angle to the said firing-point and into a position to fire the cartridge in the uppermost of the two said barrels; a second firing-plunger having an integral angularly-projecting 35 firing-point and an impact-surface adapted to be engaged by the other of the said impact-members and extending forwardly and downwardly at an angle to the said firing-point and into position to fire the cartridge in the lowermost of the two said barrels; and guide-means for each 40 of the said firing-plungers constructed and arranged to guide the same and their firing-points and impact-surfaces in a direction substantially parallel with each other, the impact-surface of each of the said firing-plungers being in substantial alignment transversely of the firearm.

2. In a multiple-barrel firearm, the combination 45 with two barrels arranged one over the other; of a frame-structure having a standing-breech provided with a pair of passages one of which is arranged in line with the uppermost of the two said barrels and the other of which is arranged in line with the lowermost thereof and both of which are in substantial parallelism; a pair of firing-plungers each having an integral angularly-projecting firing-point projectable through one of the passages in the standing-breech of the frame-structure and one thereof extending rearwardly and downwardly and the 50 other thereof extending rearwardly and upward-

ly; striker-means engageable with a rear portion of each of the said firing-plungers to forwardly propel the respective firing-points thereof; and guide-means for each of the said firing-plungers constructed and arranged to guide the same and their respective firing-points in a direction substantially parallel with each other and with the axes of the said barrels. 5

3. In a multiple-barrel firearm, the combination with two barrels arranged one over the other; of a frame-structure having a standing-breech provided with two substantially-parallel passages respectively in line with one of the said barrels, the said frame-structure also having a removable bridge-member extending thereacross 10 in rearwardly-spaced relationship with respect to the said standing-breech and provided with a guide-passage located in a plane vertically intermediate the planes of the passages in the said standing-breech; a pair of firing-plungers each 15 having a firing-point guided in one of the substantially-parallel passages in the said standing-breech, and each having its rear portion guided in the passage of the removable bridge-member of the said frame-structure; and striker-means 20 for each of the said firing-plungers adapted to impinge against the same.

4. In a multiple-barrel firearm, the combination with two barrels arranged one over the other; a pair of firing-plungers each having a 30 firing-point at its forward end and a guide-head at its rear end of substantially L-shaped form in cross-section, the guide-head of one firing-plunger being reversed in position with respect to the guide-head of the other of the said firing-plungers and interfitting therewith; and impact-means serving to independently project the said firing-plungers forwardly. 35

5. In a multiple-barrel firearm, the combination with two barrels arranged one over the other; a pair of firing-plungers each having a 40 guide-head located adjacent the guide-head of the other firing-member and each of the said guide-heads being formed with registering longitudinal grooves providing a bearing; a guide-pin bearing in the grooves of the heads of the respective firing-plungers; and a spring encircling the said guide-pin and urging the said firing-plunger rearwardly; and impact-means serving to independently project the said firing-plungers 45 forwardly. 50

6. In a multiple-barrel firearm, the combination with two barrels; a pair of firing-plungers each serving to fire one of the said barrels; a retarding-spring; and a tilting retarding-member 55 engaged with both of the said firing-plungers and engaged by the said retarding-spring intermediate its respective opposite ends; whereby each of the said firing-plungers may be moved independently of the other against the counter-urge of the said retarding-spring. 60
